ANTISINGING GAIN CONTROLLED
REPEATER

Roswell H. Herrick, Chicago, Ill., assignor to
Automatic Electric Laboratories, Inc., Chicago,
Ill., a corporation of Delaware

Application December 13, 1945, Serial No. 634,769

12 Claims. (Cl. 178—44)

1 The present invention relates generally to two-way transmission systems which employ separate amplifying means for transmitting signals in each direction and signal controlled means for governing the gain of the amplifying means and, more particularly, to improvements in the method of determining the signal direction and controlling the gain of the amplifying means accordingly.

In the usual two-way signal transmission system hybrid transformers and balancing networks are used to couple the amplifiers to the transmission line so as to prevent the output of one amplifier from affecting the input of the other amplifier. Such an arrangement will operate satisfactorily only if the impedance of the lines remains constant. However, this condition is seldom realized in practice when the line may be exposed to varying weather conditions which materially change the characteristics of the line. When the line characteristics change the hybrid network becomes unbalanced and the input and output circuits of the two amplifiers are no longer completely isolated. In order to prevent singing, the gain of the amplifiers must therefore be limited to a value such that the transmission gain is less than the transmission loss, in the loop circuit formed by the two amplifiers and hybrid transformers, under the worst conditions of unbalance likely to occur.

In order to increase the usable gain of the amplifiers various methods have been proposed for automatically adjusting the gain in response to the arrival of a signal at the input of either of the amplifiers so as to increase the gain of the active amplifier and reduce the gain of the inactive amplifier. A novel approach to this problem is disclosed in my copending application, Serial No. 533,205; filed April 28, 1944, now Patent No. 2,468,552, issued April 26, 1949, wherein it is proposed to insert a T pad in each line and operate the gain control circuits in accordance with the sense of the difference in signal voltages appearing across the line on either side of the associated T pad. The same control principle is employed in the present case wherein the inherent loss in a hybrid transformer is employed to determine the signal direction in place of T pads. The improved stability of the former system is retained while increased efficiency is secured through the elimination of the loss introduced by the insertion of the T pads in each line.

The principal object of the present invention is to provide an improved control circuit for governing the gains of the amplifiers in a two-way

2 voice repeater in accordance with the direction of signal transmission.

A feature of the above mentioned control circuit is the provision of a novel circuit arrangement for deionizing a gaseous discharge gain control tube in a voice repeater in response to the cessation of signal transmission.

Another feature of the control circuit is the provision of means for automatically regulating the gain of the control amplifiers in a voice-controlled switching system in accordance with the signal strength to prevent overloading thereof and consequent false operations.

Other objects and features of the invention will appear upon a further perusal of the specification taken in conjunction with the accompanying drawing which illustrates the invention in the form of a schematic diagram.

In the illustrated embodiment of the invention two oppositely directed amplifiers are coupled to the east and west sections of a transmission line by the usual hybrid transformers and balancing networks. A signal direction discriminating circuit is associated with each hybrid transformer. Each of these circuits is arranged to develop two direct current control potentials of polarities dependent upon the direction of signal transmission through the associated hybrid transformer. The direct current control potentials developed by each discriminator are combined and used to fire either of two gaseous discharge tubes dependent on the signal direction. Each gaseous discharge tube is arranged to enable one amplifier and disable the other. A vacuum tube and relay circuit is associated with each gaseous discharge tube to deionize it upon cessation of signal transmission. Duplicate discriminators are employed to provide equal sensitivity for either direction of signal transmission.

Referring now more particularly to the drawing, there is shown an E-W amplifier and a W-E amplifier coupled to the lines E and W by hybrid transformers 10 and 11 in the usual manner. The discriminators 1 and 2 are associated with the hybrid transformers 10 and 11, respectively, to determine the direction of signal transmission therethrough. The gaseous discharge gain control tubes and associated vacuum tubes and relays are shown in the center of the drawing. Each of the hybrid transformers 10 and 11 includes a pair of center-tapped secondary, or line, windings and a primary, or plate, winding. Discriminator 1 includes two vacuum tubes 12 and 13, the first of which has its grid circuit coupled to the primary winding of hybrid transformer

10 and the second of which has its grid circuit coupled to line W through transformer 14. The primary to secondary turns ratio of transformer 14 is the same as the total secondary to primary turns ratio of hybrid transformer 10.

Now when a signal is impressed on the primary winding of transformer 10 the voltage induced in the secondary windings is divided equally between the balancing network 15 and the line W. The voltage induced in the secondary winding of transformer 14 will therefore be equal to one-half the voltage across the primary of transformer 10. If a signal is received over line W the voltage which appears across the primary of transformer 14 will divide between the balancing network 15 and the secondary windings of transformer 10 in direct proportion to their impedances. Assuming that the impedance of the output circuit of the E-W amplifier as viewed from the secondary of transformer 10 is equal to the impedance of the balancing network 15, which is in turn equal to the impedance of line W, then the line voltage will divide equally between the balancing network 15 and the secondary windings of transformer 10. This is the usual condition since the optimum load for a power amplifier tube is approximately twice the plate resistance of the tube. The voltage induced in the secondary of transformer 14 will therefore be twice that induced in the primary of transformer 10. Thus it may be seen that for E-W signal transmission the voltage impressed on the grid of tube 12 will be twice that impressed on the grid of tube 13, and for W-E signal transmission the voltage impressed on the grid of tube 13 will be twice that impressed on the grid of tube 12. A slightly higher ratio is actually realized since the hybrid transformer 10 is not 100% efficient. Vacuum tubes 12 and 13 amplify the voltages impressed on their grids and develop corresponding voltages in the secondary windings of the transformers connected in their plate circuits. The voltages developed in these secondary windings are rectified and differentially combined in each of two control circuits. Thus winding 16 is connected across resistor 24 through rectifier 20, which is poled so as to make the upper end of resistor 24 positive with respect to the lower end thereof, and winding 18 is connected across resistor 25 through rectifier 21, which is poled so as to make the upper end of resistor 25 negative with respect to the lower end thereof. The voltage between the upper end of resistor 24 and ground will therefore be positive or negative depending on which tube, 12 or 13, receives the greater signal voltage. Windings 17 and 19 are similarly connected across resistors 26 and 27 through rectifiers 22 and 23, respectively, so that the voltage between the lower end of resistor 27 and ground is equal in magnitude but opposite in polarity to that between the upper end of resistor 24 and ground. Small condensers 28 and 29 are provided for filtering these voltages.

Discriminator 2 is identical to that just described and operates in the same manner to produce voltages of the polarities indicated across resistors 30 to 33, which voltages are filtered by small condensers 34 and 35. For east to west signal transmission the voltages across resistors 24, 26, 30 and 32 predominate over the voltages across resistors 25, 27, 31 and 33 thereby making points A and B positive and negative, respectively, with respect to ground. Similarly, for west to east signal transmission points A and B become negative and positive, respectively.

When point A is made positive in response to speech signals received over line E, gas discharge tube 36 fires and the associated vacuum tube 37 is rendered conductive. Prior to the time that tube 36 fired, the current flowing through resistor 38 from the plate supply lead (+B) in series with resistor 39 is such that the voltage impressed on the screen grid of tube 40 causes the E-W amplifier to have a desired standby gain. Similarly the voltage impressed on the screen grid of tube 41 from resistor 42 causes the W-E amplifier to have a desired standby gain. Normal voltages are impressed on the cathodes of tubes 40 and 41 from resistors 42 and 38, respectively, at this time. When tube 36 fires it increases the current flow through resistor 38 thereby raising the screen grid voltage of tube 40 and the cathode voltage of tube 41 to increase the gain of the E-W amplifier by a predetermined amount and to decrease the gain of the W-E amplifier by a corresponding amount. As relay 43, which is connected in the anode circuit of gas discharge tube 36, is rendered slow-to-operate by means of a copper slug, relay 44, which is connected in the anode circuit of tube 37, will operate first in response to the positive control voltage on point A. When relay 44 operates it connects condenser 45 across its winding at contacts 46 to render the relay slow-to-release, and closes an alternative circuit to relay 43 at contacts 47. Relay 43 subsequently operates and opens a further point in the initial anode circuit for tube 36 at contacts 48. When speech transmission ceases the positive potential on the grids of tubes 36 and 37 rapidly falls to zero, thereby rendering tube 37 nonconductive. The condenser 45 connected in multiple with relay 44 renders it slow-to-release in order to provide a short "hangover" interval, whereby the amplifier gains will not be affected by the brief interruptions normally occurring in conversation. If speech transmission is interrupted for a longer interval than the "hangover" interval, relay 44 will release and interrupt the circuit to relay 43 in series with tube 36 at contacts 47. Tube 36 is instantly deionized thereby stopping the increased current flow through resistor 38 to restore the amplifier gains to normal by lowering the screen voltage of tube 40 and the cathode voltage of tube 41. Relay 43 restores and recloses the anode circuit of tube 36 at contacts 48. Tube 36 does not fire again at this time as the potential impressed on its control electrode is below the critical value necessary to initiate a discharge therein.

When speech signals are received over line W, point B becomes positive and point A becomes negative. The positive potential of point B causes tube 49 to become conductive and causes a discharge to be initiated in gas discharge tube 50. The increased current flow through resistor 42, caused by the ionization of tube 50, raises the screen grid voltage of tube 41 and the cathode voltage of tube 40. The gain of the W-E amplifier is thereby increased a predetermined amount while the gain of the E-W amplifier is reduced by a corresponding amount. Relay 51 operates, connects condenser 52 in multiple with its winding at contacts 53 to render the relay slow to release, and closes an alternate circuit to tube 50 at contacts 54. Relay 55 operates after a brief delay and opens a further point in the initial anode circuit for tube 50 at contacts 56. When the signal transmission ceases the potential of point B rapidly decays to zero. Tube 49 becomes non-conductive causing relay 51 to restore after

the "hangover" interval and opens the anode circuit of tube 50 at contacts 54. Tube 50 is thus deionized causing the gains of the amplifiers to be returned to normal. When relay 55 subsequently restores it recloses the anode circuit for tube 50 at contacts 56.

The voice-operated gain control is arranged to permit break-in operation. Thus if speech transmission is taking place in the east-to-west direction, tube 36 will be ionized to enable the E-W amplifier and disable the W-E amplifier. If speech signals are received over line W at this time, they will tend to reverse the polarity of points A and B. The party who was speaking first has an advantage because the speech signals received over line E are amplified to a high degree in the E-W amplifier before they affect discriminator 1. On the other hand, the speech signals received over line W are amplified to a lower degree in the W-E amplifier before they affect discriminator 2. Speech signals from either direction acting directly on the discriminators without amplification have equal effects. Thus it is necessary that the signals received over line W be stronger than those received over line E in order to reverse the polarity of points A and B to thereby initiate a discharge in tube 50. When tube 50 fires it raises the screen grid voltage of tube 41 and the cathode voltage of tube 40, thereby disabling the E-W amplifier. When tube 36 is deionized it lowers the screen grid voltage of tube 40 and the cathode voltage of tube 41, thereby further disabling the E-W amplifier and enabling the W-E amplifier.

Because the voltages impressed on the input of each discriminator are much greater for one direction of speech transmission than the other due to amplification in the E-W, or W-E, amplifiers, it is desirable that some provision be made to avoid overloading the discriminators. The discriminators therefore include an automatic gain control circuit. In the absence of such a circuit the value of the signal voltages impressed on the discriminator would have to be limited to a value below the overload point for the direction of signal transmission which produces the maximum signal. The sensitivity of the discriminator would then be greatly reduced for the opposite direction of signal transmission. The automatic gain control circuit enables maximum sensitivity to be attained for either direction of signal transmission. The potential developed across the primary of transformer 10, during signal transmission in either direction, is impressed on resistors 57 and 58 in series through condenser 59. The voltage appearing across resistor 57 is impressed on resistor 60 through rectifier 61. A unidirectional potential proportional to the strength of the signals impressed on the input of discriminator 1 is thereby developed across resistor 60. Condenser 62 is shunted across resistor 60 to prevent speech components from appearing thereacross. The voltage across resistor 60 is impressed on the grids of tubes 12 and 13 to vary the gain thereof inversely with the strength of the speech signals impressed thereon. A similar automatic gain control circuit is provided for discriminator 2.

While in the system as described the gain of one amplifier is decreased when the gain of the other is increased, it should be understood that the standby gain may be made sufficiently low so that when the gain of either amplifier is increased the net loop gain will be less than the net loop loss without decreasing the gain of the other

amplifier. For example, the amplifiers may be completely blocked until speech transmission occurs. It is usually preferable to provide some standby gain, however, in order to minimize the effects of speech-clipping. It should therefore be understood that terms such as enabling or disabling employed in the claims are not to be restricted to amplifiers which are normally blocked completely.

Having described and illustrated the invention, what is considered novel is pointed out in the appended claims.

What is claimed is:

1. In a two-way transmission system including two oppositely directed voice repeaters connected between two lines by hybrid transformers, control means operative to increase the gain of either repeater, a signal direction discriminator differentially coupled to one of the lines and to the primary winding of the corresponding hybrid transformer, said discriminator operated in response to signal transmission in either direction to operate said control means so as to increase the gain of the active repeater.

2. In a two-way transmission system including two oppositely directed voice repeaters connected between two lines by hybrid transformers, control means operative to increase the gain of either repeater, two signal direction discriminators each differentially coupled to one of the lines and to the primary winding of the corresponding hybrid transformer, said discriminators concurrently operated in response to signal transmission in either direction to operate said control means so as to increase the gain of the active repeater.

3. In a two-way transmission system including two oppositely directed voice repeaters connected between two lines by hybrid transformers, control means operative to concurrently vary the gains of the repeaters in opposite senses, a signal direction discriminator differentially coupled to one of the lines and to the primary winding of the corresponding hybrid transformer, said discriminator operated in response to signal transmission in either direction to operate said control means so as to increase the gain of the active repeater and decrease the gain of the inactive repeater.

4. In a transmission system including a bilateral signal transmission channel and two oppositely directed unilateral signal transmission channels coupled thereto by a hybrid transformer, a signal direction discriminator differentially coupled to the bilateral channel and to the primary winding of the hybrid transformer, means included in each of the unilateral channels for varying the transmission efficiency thereof, said discriminator operated in response to signal transmission in either direction to cause said means to increase the transmission efficiency of the active unilateral channel.

5. In a signal transmission system including a bilateral signal transmission channel, a balancing network, a three winding transformer, two voice repeaters, two of the windings of said transformer being serially connected between said bilateral channel and said balancing network, the input circuit of one of said repeaters being connected between taps on said two windings, and the output of the other repeater being connected to the third winding of said transformer, means for deriving one voltage from the bilateral channel in response to signal waves, means for deriving a second voltage from the third winding of the transformer in response to signal waves, the ratio between said two voltages being greater or less

than one depending on the signal direction, and means for increasing the gain of either one of the repeaters in accordance with whether said ratio is greater or less than one.

6. In a two-way transmission system terminating two lines and including two oppositely directed voice repeaters, means for deriving one signal voltage in response to incoming signal waves transmitted over one of said lines in one direction and for deriving a second signal voltage in response to signal waves received from the output of the other of said lines during signal transmission in the opposite direction, the ratio of said first signal voltage to said second signal voltage being greater than one for signal transmission in said one direction and the ratio of said first signal voltage to said second signal voltage being less than one for signal transmission in said opposite direction, a control circuit for each repeater, rectifying means for producing a unidirectional potential in each of said circuits from each of the derived signal voltages, said rectifying means being poled so that the net unidirectional potential in each control circuit is positive or negative dependent on the said ratio and direction of signal transmission, and means governed in accordance with the polarity of the net unidirectional potentials in each of said control circuits for regulating the gain of the corresponding repeater.

7. In a transmission system including a bilateral signal transmission channel and two oppositely directed unilateral signal transmission channels coupled thereto in conjugate relationship, means for deriving one speech signal voltage from the bilateral channel and another speech signal voltage from one of said unilateral channels, said derived speech signal voltages having a ratio greater or less than one depending on the direction of signal transmission, a voice repeater in each unilateral channel, a control circuit for each repeater, rectifying means for producing a unidirectional potential in each of said circuits from each of the derived signal voltages, said rectifying means being poled so that the net unidirectional potential in each control circuit is positive or negative dependent on said ratio and the direction of signal transmission, and means governed in accordance with the polarity of the net unidirectional potentials in each of said control circuits for regulating the gain of the corresponding repeater.

8. In a transmission system including a bilateral signal transmission channel and two oppositely directed voice repeaters coupled thereto by a hybrid transformer, a signal direction discriminator differentially coupled to the bilateral channel and to the primary winding of the hy-

brid transformer, and means controlled by said discriminator in response to signal transmission in either direction for governing the gains of the repeaters accordingly.

9. A transmission system as claimed in claim 8 wherein said signal direction discriminator includes amplifying means, and means operative to regulate the gain of the amplifying means in accordance with the strength of the speech signals impressed thereon.

10. In a transmission system including two oppositely directed voice repeaters, a voice-operated control circuit having a signal direction discriminator and including amplifying means in said discriminator for governing the gains of said repeaters in accordance with the direction of signal transmission, and means for varying the gain of said amplifying means in said discriminator inversely with the voice signal strength over said control circuit.

11. A two-way transmission system as claimed in claim 6 in which said last means includes a gaseous discharge tube operated by a positive net unidirectional potential, said gaseous discharge tube having an anode circuit including a resistor through which current flows in response to the operation thereof, and means responsive to the flow of current through said resistor for increasing the gain of the corresponding repeater.

12. A transmission system as claimed in claim 4 in which said means includes a gaseous discharge tube operated in response to the operation of said signal direction discriminator, a vacuum tube also operated in response to the operation of said signal direction discriminator, and means including said vacuum tube for maintaining said gaseous discharge tube operated a certain interval independent of the operation of said discriminator to thereby maintain the increased efficiency of the active unilateral channel for a certain interval after the cessation of signal transmission.
